UNITED STATES PATENT OFFICE.

JOHN W. WILLING, OF NANTICOKE, MARYLAND.

BOAT-DETACHING MECHANISM.

SPECIFICATION forming part of Letters Patent No. 373,325, dated November 15, 1887.

Application filed April 6, 1887. Serial No. 233,906. (No model.)

To all whom it may concern:

Be it known that I, JOHN W. WILLING, of Nanticoke, in the county of Wicomico and State of Maryland, have invented certain Im- 5 provements in Boat-Detachers, of which the following is a specification.

Figure I is a front view of the detacher closed, and Fig. II is a side view of the same. Fig. III is a view of the detacher open.

10 Similar letters of reference indicate similar parts in all the figures.

A and B are crossed levers united to a strap, C, by means of a pivotal bolt, a. This strap is adapted for attachment in any suitable manner to a block suspended from the boat-davit, which is not shown. The upper arms of the levers A and B are provided with weights b and c, which serve to open or separate the lower arms, e and f, as shown in Fig. III. The 15 said lower arms are adapted for connection by means of a bolt, D, pivoted to the arm f and fitted to pass through a hole, g, in the other arm, e, as shown in Fig. I. One of the lower arms, preferably the one e, is furnished with a projection, h, having a ring, k, at its end, to which the detaching-line l is secured. The eyebolt E is fastened to the boat, which is not shown, and rests on the bolt D.

The boat is detached automatically as it 20 strikes the water in view of the balls b and c opening or separating the arms e and f, or by

hand by pulling the arm e from or over the end of the bolt D by means of the line l.

It is obvious that the same effect is pro- 25 duced by pulling the arm f, with its bolt D, from connection with the arm e.

When it is desired to lock the detacher, a pin, m, is passed through the bolt D and the projection h of the arm e, as shown in dotted lines in Fig. I. This pin is connected to the 40 ring k by means of a small line to prevent its being lost when not in use.

I claim as my invention—

1. In a boat-detacher, two weighted crossed levers pivoted to a suspensory strap and connected at their ends by means of a bolt which is pivoted to one of the said levers and fitted to pass through the other, substantially as and for the purpose specified. 45

2. In a boat-detacher, a pair of crossed le- 50 vers pivoted to a suspensory strap connected at their lower ends by means of a bolt pivoted to one of the said levers and adapted to pass through the other, one of the said levers being provided with a ring or eye, to which a 55 detaching-line may be secured, substantially as and for the purpose specified.

JOHN W. WILLING.
